UNITED STATES PATENT OFFICE.

EVERETT W. HOUSE, OF ELIZABETH, NEW JERSEY.

SUPPORTING RACK.

Application filed January 20, 1926. Serial No. 82,520.

This invention relates to supporting racks especially designed for holding books, files, or other articles in a vertical position on a desk.

5 Some of the principal objects of the invention reside in the provision of a rack which affords a wide range of adjustment to accommodate articles of various thickness; a rack which facilitates the insertion 10 of the articles and removal of the articles especially those of a limp nature; a rack which is simple in its construction and mode of use; and a rack which is highly efficient in its purpose.

15 With the above recited and other objects in view, reference is had to the following specification and accompanying drawings in which there is exhibited one example or embodiment of the invention which is in no 20 way intended as a limitation upon the scope of the appended claim as it is to be clearly understood that variations and modifications which properly fall within the scope of said claim may be resorted to when found 25 expedient.

In the drawings—

Figure 1 is a perspective view of a rack constructed in accordance with the invention, illustrating several ways in which the same may be used and adjusted, and

Fig. 2 is an enlarged fragmentary transverse sectional view therethrough.

Referring to the drawings by characters of reference, the rack includes a substantially oblong base 10, which is formed with a double row of apertures 11 adjacent the opposite longitudinal side edges thereof, the apertures in each row being spaced apart an equal distance to the spacing of the apertures of each double row. The rack further includes partition elements or members in the nature of inverted U-shaped wires or rods 12, each including a pair of legs 13 joined at the upper end by a substantially semi-circular bight 14. The partition members are constructed of a material which is resilient whereby the lower free ends of the legs 13 when fitted within an adjacent pair of openings 11, will frictionally coact with the openings to prevent casual displacement of the partition members from the base. The uniform spacing of the apertures 11 permits the positioning of the partition

members 12 either longitudinally of the base, as illustrated at the right hand of Fig. 1, 55 or transversely of the base, as illustrated at the left of Fig. 1, the latter arrangement affording a maximum capacity for the rack. The former arrangement, namely, where the partition members are disposed longitudinally of the rack, or in a plane parallel with the longitudinal side edges, presents the semi-circular or curved bights in such a manner as to afford a flared entrance to the article-receiving space between adjacent 60 pairs of partition members, which arrangement greatly facilitates the introduction of the articles, such as limp bound books, to the receiving spaces.

In order to prevent wear or scratching 70 and marring of the finish of the upper face of the base by the articles supported by the rack, wear strips or beads 15 are provided on the upper face of the base preferably adjacent the longitudinal side edges. The 75 base may be further formed with a felt covering 16 on the lower face to prevent marring or scratching of the surface upon which the rack is mounted.

It is obvious from the foregoing construction that the partition members may be relatively spaced apart various distances to accommodate articles of various thickness at the option of the user.

What is claimed is:

A supporting rack including a base having a pair of rows of vertically disposed apertures in its upper face adjacent each opposite marginal edge, the openings in each row being spaced apart the same distance 90 as the spacing between the rows of each pair, and a plurality of inverted U-shaped resilient partition members each having a pair of legs joined by a bight at the upper end and having free lower extremities normally 95 spaced apart a distance approximately equal to the distance of the spacing of adjacent openings, the lower extremities of each of said members being engaged in two adjacent openings, the spacing of the openings being 100 such that the said members may be selectively anchored in the openings to dispose the bights respectively longitudinally or transversely of the base.
